UNITED STATES PATENT OFFICE.

ORA L. BURCH, OF LITTLETON, COLORADO.

SPARK-PLUG TESTER.

Application filed May 22, 1923. Serial No. 640,748.

To all whom it may concern:

Be it known that I, ORA L. BURCH, citizen of the United States, residing at Littleton, in the county of Arapahoe and State of Colorado, have invented certain new and useful Improvements in Spark-Plug Testers, of which the following is a specification.

This invention relates to an improved spark plug tester and seeks, as one of its 10 principal objects, to provide a device of this character which may be employed in conjunction with the primary and secondary posts of one of the induction coils of a Ford vehicle for testing the plugs of the vehicle 15 engine.

The invention seeks, as a further object, to provide a device which may be permanently mounted upon the coil posts of one of the coils without interfering with the functioning of the ignition system of the 20 vehicle but which will utilize the coil in testing a plug, whenever it is desired to make a test.

And the invention seeks, as a still further 25 object, to provide a device which may be readily applied and which will be of simple construction so that the device may be produced and sold at moderate cost.

Other and incidental objects will appear 30 hereinafter.

In the drawings:

Figure 1 is a perspective view of my improved spark plug tester.

Figure 2 is an enlarged vertical sectional 35 view showing the device mounted upon the primary and secondary posts of one of the coils of a Ford vehicle, and

Figure 3 is a diagrammatic view showing 40 a portion of the ignition system of the vehicle and illustrating the manner in which the device is interposed in said system.

In carrying the invention into effect, I employ an oblong body plate or member 45 10 which is formed of a strip of suitable insulating material and mounted upon said plate at the lower end thereof is an angle bracket 11 riveted or otherwise secured to the plate. Formed through the plate and through said bracket is an opening 12 and 50 formed in the bracket near the free end thereof is a similar opening 13. Mounted upon the plate 10 near its upper end is a spring clip 14 which may, like the bracket 11, be riveted or otherwise secured to said plate. This clip is provided with companion 55 arcuate spring fingers 15 preferably formed

at their outer ends with laterally directed lips 16 and rising from the clip is a switch arm 17 offset to extend in parallel relation to the body plate. Formed through the 60 plate and through said arm at its lower end portion is an opening 18 similar to the opening 12 at the lower end of the plate. In conjunction with the switch arm I employ a conductor 19 which may be formed of a low resistance insulated wire and soldered or otherwise secured to said wire at one end thereof is a terminal 20 secured to the upper 65 end of the body plate 10 by a rivet or other suitable fastening device 21 forming a contact post in the rear of the switch arm.

In order to clearly bring out the manner of use of my improved spark plug tester, I have, in Figures 2 and 3 of the drawings, 70 shown the device applied. As previously intimated, the device is especially designed for use in connection with Ford vehicles and in Figure 2 I have conventionally shown the dash of such a vehicle at 22. The usual coil box of the vehicle is indicated at 23 and projecting from the coil box forwardly through the dash are the usual coil posts, the 75 posts of the first coil, or the coil at the right, being indicated at 24 and 25 respectively. In mounting the improved device, the nuts upon these posts are removed when the forward ends of the posts are inserted 80 through the openings 12 and 18 of the device. The body plate 10 will thus abut the usual porcelains upon the posts so that 85 when said nuts are again applied, the device will be rigidly mounted upon said posts to extend vertically therebetween.

In replacing the nuts the usual primary and secondary circuit wires 26 and 27 of the coil 90 are connected with the posts by said nuts. Thus, under ordinary conditions, the coil 95 will function in the same manner as though the device were not mounted upon the coil posts, the wire 26, along with the primary circuit wires of the other coils of the coil box, being connected to the engine commutator 30 which, as is known, functions to electrically ground the primary circuits of the several coils in proper synchronization. After the body plate has been 100 arranged in position the conductor 19 is extended across to the usual center radiator brace rod 28 of the vehicle and wrapped about said rod for electrically grounding 105 the conductor.

In Figure 2, I have shown a conventional

plug 29 in position upon the device so as to be tested. As illustrated, the plug is inverted, when the center electrode of the plug is inserted through the opening 13 in 5 the bracket 11 while the base end of the plug is engaged between the spring fingers 15 of the clip 14. The usual switch of the ignition system of the vehicle is then turned to close the primary circuit of said system 10 from the battery of the vehicle through the coils. Accordingly, by then flexing the switch arm 17 to engage the contact 21, the primary circuit of the first coil will be closed through the ground conductor 19 15 while the secondary circuit of said coil will be closed through the center electrode of the plug, the clip 14, the switch arm 17, contact 21, and conductor 19 to ground. Thus, if the plug is in good condition, a 20 steady hot spark will be caused to jump from the center electrode of the plug across to the coating electrode upon the plug shell. On the other hand, if the plug is defective, either no spark at all or, at least, a 25 very weak spark will occur between the electrodes of the plug, thus indicating the faulty condition of the plug. I accordingly provide a device whereby each of the plugs of an engine may be efficiently tested while 30 the presence of the device upon the vehicle will in no way hamper the normal operation of the ignition system of the vehicle.

Having thus described the invention, what is claimed as new is:

- 35 1. The combination with an induction coil, and primary and secondary circuit posts associated therewith, of contact means electrically connected permanently with one of said posts, contact means electrically connected permanently with the other of said posts to engage the shell of a spark plug having one of the coating electrodes thereof in contact with said first mentioned means, and a switch exposed to be manually flexed for electrically grounding the primary circuit and closing the secondary circuit of the coil through the electrodes of the plug.
- 40 2. In a vehicle engine ignition system, the combination of an induction coil, primary

and secondary circuit posts associated therewith, means mounted upon said posts and electrically connected permanently therewith to accommodate a spark plug having one of the coating electrodes thereof in 55 circuit with the secondary post, and a switch exposed to be manually flexed for electrically grounding the primary circuit of the coil as well as closing the secondary circuit of said coil through the electrodes 60 of the plug.

3. A spark plug tester including companion contact elements for permanent mechanical and electrical connection to the primary and secondary circuit posts of an induction coil to receive a spark plug having one of the coating electrodes thereof in circuit with the secondary post, and a switch exposed to be manually flexed for closing a circuit through the primary post as well 70 as closing a circuit through the secondary post and through the electrodes of the plug.

4. A spark plug tester including a body member, spaced contact elements carried thereby for permanent mechanical and electrical connection to the primary and secondary posts of an induction coil and formed to receive a spark plug in circuit with said elements, and a switch exposed to be manually flexed for electrically grounding one 80 of said elements.

5. A spark plug tester including a strip of insulating material apertured near its ends to receive the primary and secondary posts of an induction coil therethrough, a 85 bracket near one end of the strip apertured to receive one of said posts, and a spring clip near the opposite end of the strip to engage the shell of a spark plug resting on said bracket and having the center electrode thereof engaged with the bracket, said clip being formed with an upstanding resilient switch arm apertured to receive the other of said posts and adapted to be manually flexed for closing a circuit through the 90 plug.

In testimony whereof I affix my signature.

ORA L. BURCH. [L.S.]
